(57) **CLAIM**

The ornamental design for an interface flange for a bottle as shown and described.

DESCRIPTION

FIG. 1 is a top perspective view of an interface flange for a bottle showing the new design in use with exemplary environmental subject matter;

FIG. 2 is another top perspective view thereof, shown with the exemplary environmental subject matter removed, to show aspects of the design not visible when combined;

FIG. 3 is a bottom perspective view thereof;

FIG. 4 is a front view thereof;

FIG. 5 is a back view thereof;

FIG. 6 is a right side view thereof;

FIG. 7 is a left side view thereof;

FIG. 8 is a top view thereof; and,

FIG. 9 is a bottom view thereof.

The broken lines are shown for the purpose of illustrating both parts of the article as well as environmental subject matter. The dot-dash broken lines represent the boundaries of the claim. None of the broken lines form part of the claimed design.
